United States Patent Office

Des. 186,835
Patented Dec. 8, 1959

186,835

PLASTIC SHEET MATERIAL

Arthur D. Sylvester and Arno H. Scheiding, Rowayton, Conn., assignors to L. E. Carpenter & Co., Inc., Wharton, N.J., a corporation of New Jersey

Application September 18, 1956, Serial No. 42,985

Term of patent 14 years

(Cl. D87—3)

Fig. 1.

Fig. 2.

Fig. 1 is a plan view of a piece of plastic sheet material embodying our new design; and

Fig. 2 is a vertical sectional view, taken along the line II—II of Fig. 1.

We claim:

The ornamental design for a plastic sheet material, substantially as shown.
